ATTORNEY

UNITED STATES PATENT OFFICE.

GEORGE M. ASK, OF CORNING, CALIFORNIA.

WINDMILL.

Application filed June 19, 1922. Serial No. 569,201.

To all whom it may concern:

Be it known that I, GEORGE M. ASK, a citizen of the United States, and resident of Corning, in the county of Tehama and State 5 of California, have invented certain new and useful Improvements in Windmills, of which the following is a specification.

It is the object of my invention to provide a wind mill structure that will automatically 10 adapt itself to varying wind pressures and thereby maintain a substantially uniform pumping speed.

It is another object of my invention to provide a wind mill structure of the character 15 indicated that may be adjusted to operate at a given speed and that will automatically adjust itself to maintain that given speed under varying wind velocities.

It is a still further object of my invention 20 to provide a device of the character hereinbefore set forth that will be simple and economical in form, construction and method of operation.

In the drawing:—

25 Figure 1 is a side elevation of my improved form of wind mill, parts being broken away.

Figure 2 is a plan view of the same.

Figure 3 is an enlarged detail of the vane 30 adjusting carriage taken on line 3—3 of Figure 1, parts being broken away.

Referring more particularly to the drawing, I indicate at 1 a portion of a suitable supporting framework having a member 2 35 revolvably mounted thereon and carrying a frame 3 lying in a horizontal plane.

Depending from one end of frame 3 are lugs 4 having an arm 5 pivotally mounted thereon at 6, said arms extending upwardly 40 and outwardly from frame 3 to a point 7 upon which is secured a weight 8. At the rear of arm 5 is attached a cable 9 as at 10. To a lug 11 formed on arm 5 below its pivotal point 6 is secured a vane 12 lying in a plane at right angles to the vertical plane in 45 which arm 5 swings.

At 13 is shown a tube mounted on frame 3 by brackets 14, said tube lying in the vertical plane in which the longer axis of frame 3 50 lies, and slightly above frame 3. Mounted to reciprocate in tube 13 is a rod 15 revolvably connected to carriage 16 mounted to reciprocate on guides 17, carriage 16 being connected by link 18 to pivotal point 19 on arm 5 between the pivotal point 6 of arm 5 and its 55 weighted point 7.

On the outer end of rod 15 is a fitting 20 to which are pivotally attached rods 21.

Since two vanes of the windmill are similar in construction but one will be described 60 in detail, the other being indicated by similar numerals followed by an appropriate letter.

Rigidly mounted on the outer end of tube 13 is a collar 22 carrying a head 23, the head 23 having a bracket 24 rigidly mounted thereon. On bracket 24 is pivotally mounted a vane 25 by means of bearings 26, the said vane 25 being pivotally connected to rod 21 at a point intermediate its pivotal point and 70 one end. Vane 25 is suitably curved toward the wind and braced by elements 27. The two vanes 25—25^a while similar in construction are mounted on brackets 24—24^a in such a manner as to slope away from the 75 wind equally but in opposite directions. Since the wind pressure is equal on both vanes from a wind blowing in the direction indicated by the arrow, it follows that the vanes, the head 23 and the tube 13 upon 80 which they are mounted and rod 15 are caused to rotate as a unit.

Passing vertically through the pivotal point of frame 3 is a tube 28, and encompassing tube 28 is a frame 29 supported on frame 3 by a brace 30. Frame 29 supports bearings 31 in which operates a tube shaft 32 carrying a gear 33 meshing with a pinion 34 on tube 13. Gear 33 carries a pin 35 on which is pivotally mounted a rod 36 pivotally attached to a guide member 37 mounted to reciprocate vertically on guide rods 38 and having the pump rod 39 attached thereto, the said pump rod 39 passing down through tube 28 to the pump not shown. 95 Guide rods 38 are rigidly mounted on frame 29 carrying a terminal pulley 40 over which cable 9 passes, the said cable 9 passing down through tube 28 to any convenient place where a suitable weight as 41 is attached 100 to it.

In operation it will first be assumed that the pump is to be operated at the highest speed of which it is capable. In that case cable 9 is sufficiently weighted to throw 105 vane 12 into a vertical position and vanes 25—25^a in an extended position as shown. The pump will now operate at full speed under sufficient wind pressure. If, however, the wind should develop a pressure 110 greater than the device is built to withstand, then this excessive pressure operates

vane 12 inwardly against the pull of counter weight 41, thereby automatically moving vanes 25-25^a into a position such as indicated in dotted lines at 42 where the surface presented to the wind is greatly reduced.

If it is desired to operate the pump to deliver a certain given quantity of water as a maximum, then a proper weight 41 is mounted on cable 9 to determine the speed limit of the pump. If the wind should develop a uniformly high pressure too great for the conditions presented then the vane 12 is forced inwardly a certain distance so that the vanes 25-25^a will present just sufficient surface to the wind to develop the required speed of rotation of tube 18 and through the mechanism described, the required speed of reciprocation of pump 20 rod 32.

When the pump is to be put out of operation entirely the cable 9 is operated to throw vane 12 flat up against the bottom of frame 3, thereby folding vanes 25-25^a 25 into a position where no effective resistance to the wind is offered.

It may now be readily seen that by means of the mechanism set forth the maximum speed of the wind mill may be predetermined so that any given maximum quantity

of water may be pumped, the pumping of a greater amount of water than that desired being effectually prevented by the automatic adjustment of vanes 25-25^a through the movement of vane 12 under a wind pressure sufficient to overbalance weight 41.

It is to be understood, of course, that while I have herein shown and described one particular embodiment of my invention, changes in form, construction, proportions and method of operation may be made within the scope of the appended claim.

I claim:

A wind mill comprising a structure mounted to rotate in a horizontal plane, vanes adjustably mounted to revolve as a unit on one end of said structure and in a vertical plane, a vane normally lying in a plane at right angles to the axial plane of said structure pivotally mounted upon the 50 opposite end thereof and below the axis of said structure, an arm carried by said vane extending to the opposite side of its pivotal point, a weight carried by said arm, a weighted cable connected to said arm to counterbalance said weight, and means for effecting the adjustment of said first vanes through the movement of said second vanes.

GEORGE M. ASK.
